UNITED STATES PATENT OFFICE

MARTIN NYSTROM, OF CHICAGO, ILLINOIS, ASSIGNOR, BY MESNE ASSIGNMENTS, TO
UNITED RESEARCH CORPORATION, OF LONG ISLAND CITY, NEW YORK, A CORPORA-
TION OF DELAWARE

SOUND REPRODUCING DEVICE

Original application filed April 10, 1926, Serial No. 101,186. Divided and this application filed March 31,
1928. Serial No. 266,221.

This application is a division of my co-pending application, Serial No. 101,186, filed April 10, 1926.

5 My invention relates to devices for reproducing sound and has a special relation to sound boxes for phonographs.

An object of my invention is to provide a 10 device for securing a stylus bar to a diaphragm of a sound box which will be light and therefore of such nature as to transmit 15 all vibrations to the diaphragm and which at the same time, will eliminate the possibility of the stylus bar tearing loose from the diaphragm or setting up undesirable vibrations therein.

15 Another object of my invention is to provide a mounting for a stylus bar which will permit movement of the stylus bar with the least possible restraint and which will automatically take up looseness of parts so as to 20 eliminate chattering, straining of the stylus bar, and undesirable vibrations.

Still another object of my invention is to 25 eliminate looseness, end-play and chatter from the bearings of the phonograph stylus bar.

A further object is to reduce the friction 30 in a phonograph stylus carrying bar without introducing looseness in the bearings.

Still another object is to hold the ball races of a ball bearing stylus bar in firm contact 35 without introducing undesired friction.

Other advantages will appear as the description proceeds.

35 Referring to the accompanying drawings.

Fig. 1 represents an elevational view of a sound box embodying the invention;

Fig. 2 is a sectional view taken substantially on the line II-II of Fig. 1;

40 Fig. 3 is an enlarged detail view partly in elevation and partly in section of the connection between a diaphragm and a stylus bar;

Fig. 4 is an enlarged sectional view of the 45 connection;

Fig. 5 is an enlarged sectional view taken on the line V-V of Fig. 1;

Figs. 6 and 7 are enlarged detail views 50 showing a shank which constitutes a portion of the stylus bar;

Fig. 8 is an enlarged detail view showing the condition of a stylus bar after the shank is welded to the body of the bar.

Figs. 9, 10 and 11 are enlarged details of the stylus bar showing it immediately prior to the assembly of a supporting shaft with 55 the bar.

Mounted in a sound box casing 1 is a diaphragm composed of a very light substance such as aluminum or magnesium or an alloy of either of these metals, and having a flexible outer portion 2 approximately .002 of an inch in thickness and a rigid central portion 3 of conical shape approximately .004 of an inch in thickness. The conical central portion is slightly flattened at its apex and has an opening therethrough, through which extends a rivet composed of a light metal such as aluminum or magnesium or an alloy of either of these metals. The rivet has a head 4 which engages the inner face of the diaphragm and its outer end is countersunk in a washer 5 made of suitable material such as brass which is thus held securely against the diaphragm. 65

70 The washer has spaced slots 6 therein which receive forked ends on a shank 7 of a stylus bar, the ends being secured to the washer by means of solder 8.

75 The described devices for securing the shank of the stylus bar to the diaphragm are very light in weight, and, therefore, promote the faithfulness of the reproduction of sound by the diaphragm, yet at the same time, they are durable and will remain in operative condition after prolonged usage without disrupting the fragile diaphragm, and without any looseness developing which would impair the acoustic effect. 80

85 The shank of the stylus bar is thin and is preferably made of hard metal such as spring steel, it is welded to a stylus bar body 9 which is relatively heavy.

90 The stylus bar body has a transverse bore extending therethrough in which is secured a shaft 10 having tapered ends which project laterally, and are received in bearings 11 on the sound box casing. Each end of the shaft is supported by a series of balls 12 which permit the stylus bar to vibrate freely. 100

To prevent the shaft from deteriorating through wear, it is made of a durable metal such as hard steel.

- 5 In each bearing is a follower 13 which engages the balls and retains them in place, the followers are urged against the balls by means of a single spring which is provided with a depression 14 at each end to receive a projection 15 on the follower. The spring 10 is mounted in grooves 16 on the outer face of the bearings and is as shown at 17 bowed adjacent its ends and also between the bearings in order that it may be especially resilient. By forcing the followers inwardly, the 15 spring retains the balls in engagement with the bearings and the ends of the shaft. Thus there can be no lost motion in the pivotal movement of the stylus bar and looseness of parts is automatically taken up.
- 20 In making the stylus bar, the shank 7 is punched from sheets of metal and in its initial form is as shown in Figs. 6 and 7. The shank is then bent as shown at 18 and is twisted as shown at 19 so that the ends of the 25 shank are in a line extending perpendicularly to the plane of the main portion of the shank. The shank is then welded to a forging, through which a bore is then drilled, and in which a recess 20 is made to receive a stylus 30 21. The shaft 10 is then forced into the bore and the stylus bar is ready for assembly with the sound box. The shaft is made separate from and not integral with the stylus bar body as it is necessary to harden the shaft 35 and grind the ends thereof where they engage the balls and it would be difficult to perform the grinding operations if the shaft were an integral part of the stylus bar body.
- 40 The invention is not limited to the specific details of construction illustrated and described, which may be greatly modified without departing from the spirit of the invention, and a substantial range of equivalents is contemplated within the scope of the 45 appended claims.

What I claim and desire to secure by Letters Patent is:

- 50 1. In a mounting for a stylus bar, the combination of a sound box, a pair of bearings thereon, a stylus bar, a pivot therefor having a pair of tapered ends received in said bearings, a plurality of balls surrounding each of said ends, a follower in each bearing for maintaining pressure on the balls and holding them in operative position and a single spring engaging both of said followers and urging them against said balls.
- 55 2. In a mounting for a stylus bar, the combination of a sound box, a pair of bearings thereon, a stylus bar, a pivot therefor having a pair of tapered ends received in said bearings, a plurality of balls surrounding each of said ends, a follower in each bearing for maintaining a pressure on the balls and holding them in operative position, a single

70 spring engaging both of said followers and urging them against said balls, and releasable means for maintaining said spring in operative position with respect to said followers.

- 75 3. In a mounting for a stylus bar, the combination of a sound box, a pair of bearings thereon, each having a groove therein, a stylus bar, a pivot therefor having a pair of tapered ends received in said bearings, a plurality of balls surrounding each of said ends, a follower in each bearing for maintaining pressure on the balls and holding them in operative position and a single leaf spring having a main body portion received in said grooves and having laterally directed ends engaging said followers and urging them against said balls.
